[57] CLAIM

The ornamental design for a insect repellent and disinfectant pendant for domestic animals, as shown and described.

DESCRIPTION

FIG. 1 is a front elevational view of a insect repellent and disinfectant pendant for domestic animals embodying our new design;

FIG. 2 is a left side elevational view thereof, the right side being a mirror image of the side shown;

FIG. 3 is a rear elevational view thereof;

FIG. 4 is a top plan view thereof; and

FIG. 5 is a bottom plan view thereof.

The front is shaded to show a red colored reflector and the rear is shaded to show an amber colored reflector.

FIG. 1

FIG. 2

FIG. 3

FIG. 4

FIG. 5
